UNITED STATES PATENT OFFICE

FRED MASCH, OF BURLINGAME, CALIFORNIA, ASSIGNOR TO MONROE CALCULATING MACHINE COMPANY, OF ORANGE, NEW JERSEY, A CORPORATION OF DELAWARE

SWITCH MECHANISM FOR CALCULATING MACHINES

Application filed February 27, 1929. Serial No. 343,209.

This invention relates to a switch for controlling the circuit of an electrically driven calculating machine, and one of the principal objects of the invention is to provide a switch 5 which opens the electric circuit of the driving motor when the carriage is in any position other than its proper operating position.

Another object of the invention is to provide means for opening such switch when 10 the shift or reversing lever of the machine is in any position intermediate its two extreme positions.

Another object of the invention is to provide switch operating means which shall 15 work in conjunction with the mechanical locking-means provided in the machine and shall take effect prior to the mechanical locking-means so as to relieve the latter of unnecessary shock and strain.

20 Other objects will be apparent from the following description and appended claims.

Means for obtaining all of these objects is illustrated in the accompanying drawings in which:—

25 Fig. 1 is a top plan view of a calculating machine embodying my invention.

Fig. 2 is a vertical sectional view taken substantially on line 2—2 of Fig. 1 with certain parts left out for the sake of clearness.

30 Fig. 3 is an enlarged fragmentary side elevation of the machine showing the carriage in elevated position.

Fig. 4 is an enlarged fragmentary top plan view of the parts constituting the present 35 invention together with other actively associated parts.

Fig. 5 is a view similar to Fig. 4 but showing the shift or reversing lever moved sufficiently to open the auxiliary switch without 40 moving the mechanical lock to operative position.

Fig. 6 is a view similar to Figs. 4 and 5 but showing the shift lever moved sufficiently to open the auxiliary switch and also render 45 the mechanical lock effective.

Fig. 7 is a perspective view of the auxiliary switch and associated lever.

Like characters of reference refer to like parts in all views.

50 In the drawings, the invention is shown as

applied to a calculating machine of the type described in the patent to George C. Chase #1,566,650, issued December 22, 1925; and patent to George C. Chase #1,685,074, issued September 18, 1928; the application of 55 George C. Chase and Francis Boon, Ser. No. 262,574, filed March 17, 1928; the application of George C. Chase, Ser. No. 226,418, filed Oct. 15, 1927; and the application of E. F. Britten, Jr., Ser. No. 337,073, filed 60 February 2, 1929 to all of which reference may be had for a more complete description of the details of the calculating and driving mechanisms.

While the present invention is shown as 65 applied to a calculating machine of the well known Monroe type, it may be readily applied to other types of calculating and computing machines, and the invention is not to be considered as limited in its application to 70 the type of machine shown in the drawings.

In the well known type of Monroe machine there is a movable carriage carrying the accumulator wheels and the counter wheels; and this carriage is movable transversely of 75 the machine from one denominational position to another. In moving the carriage from one position to another it is first elevated sufficiently to disengage the mechanism carried by the carriage from the cooperating parts of the body of the machine, after which the carriage is moved laterally and then lowered into its new engaging position. There is also provided a shift or reversing lever movable to either of two operative positions, the function of this lever being to effect a reversal in the direction of 80 rotation of the counter dials with relation to the operating mechanism. In order to protect the mechanism of the machine from shocks and injury it is highly desirable that 85 the motor be rendered inactive during the transition of the carriage from one operative position to another and when the carriage is not properly seated in operating position, and during movement of the shift lever and when the shift lever is left in intermediate position.

The present device provides means for accomplishing all of these results, which 90 means will now be described in detail. 95

Referring to the accompanying drawings, and particularly to Figs. 1 and 2 thereof, 20 represents the carriage generally, the same being pivoted at 21 so that the carriage is 5 permitted a limited amount of rotary movement. While not strictly true, the rotary movement in clockwise and counter-clockwise directions may be called the rise and fall of the carriage inasmuch as the front of the 10 carriage rises and falls. The carriage carries register or accumulator dials 23, and two series of counter dials 24 and 25, the series of dials 24 being non-carrying and of the type known as "nineteen-point" counters (bearing 15 numerals from "1" to "9" in each direction from the "0" position, the numerals in one direction being differently colored from those in the opposite direction), and the series of dials 25 being provided with carrying or tens- 20 transfer mechanism, and being regular "ten-point" counters although operable in either direction.

The carriage may be moved from one position to another by a carriage shifting lever 23 26 adapted to be rotated either automatically or by hand, and carrying oppositely disposed crank pins 27 adapted to engage in serrations formed in the front of the carriage and to lift the front of the carriage, move the 30 latter to the next order position and lower the carriage into this new operative position.

The keyboard comprises a plurality of banks of digit-setting keys 27, multiplier keys 28, plus key or bar 29, minus key or bar 30, repeat and non-repeat keys 31 and 32, column correction keys 33, universal correction key 34, shift or reversing lever 35, and division lever 36. Of these, the operation of any one of the keys 28, 29 and 30 or of lever 36 40 will normally effect operation of the machine. As described fully in the application Serial Number 262,574 above referred to, the operation of any one of these instrumentalities will cause the closing of a switch shown 45 in the present application at 37, Fig. 1.

This switch 37 is wired in series with a manually operable switch 38 arranged at the motor 39. The motor 39 is connected to drive the machine when the circuit through 50 switches 37 and 38 is closed.

The mechanism thus far mentioned is fully set forth in detail in the aforementioned patents and application, to which reference may be had, the above brief outline being 55 thought sufficient for present purposes.

The present invention per se includes an auxiliary switch 40 wired in series with switches 37 and 38 and including the usual spring conductors 41 provided with contact 60 lugs 42. The tendency of the conductors is to hold the contacts 42 apart, but when the carriage is in its operative or lowered position, the front edge of the carriage bears down upon a block 43 of insulating material, 65 which block is fast on the upper face of the

upper conductor 41, thereby forcing the upper contact 42 into engagement with the lower contact 42 and closing this switch. As soon, however, as the carriage is moved from its operative position, either by the action of one of the crank pins 27 or by manually raising the carriage, the upper conductor 41 springs upwardly raising its contact 42 out of engagement with the lower contact 42, opening this switch.

Thus there is provided means for breaking the motor circuit of a calculating machine whenever the carriage is out of operative position; and while the carriage shown has a rise and fall movement which is taken advantage of in this connection, the invention is not limited to such a carriage, for, obviously, a carriage which moved rectilinearly without the rise and fall could be provided with lugs to ride onto the block 43 so as to close the switch only when the carriage was in one or another of its operative positions. Other expedients for adapting the invention to various carriages will readily occur to anyone skilled in the art.

Turning now to the shift or reversing lever 35, and referring first to Figs. 3 and 4, it will be found, as fully set forth in the above mentioned application of E. F. Britten, Jr., that in moving this lever from one to the other of its two operative positions, the lever 35 encounters one or the other of the inclined faces of a V-shaped cam 44 formed on a locking lever 45. Lever 45 is pivoted at 46 to the lower face of the keyboard 47 and is formed at its forward end with a laterally extending finger 48 which normally rests to the left of a gear wheel 49 forming part of the driving mechanism of the machine. This gear 49 is formed with a notch or recess 50 which is of considerably greater extent than the width of finger 48, and into which the finger is projected by lever 45 when the shift or reversing lever 35 is in its intermediate position, as shown in Fig. 6. A spring 50' tends constantly to rotate the lever 45 clockwise (as viewed from above) and hold it against the shift lever 35 or other suitable stop.

It will be noted that in the normal position of locking lever 45, Fig. 4, the end of finger 48 is an appreciable distance from the inner face of gear 49, and that consequently the shift lever 35 can move cam 44 to a considerable extent before finger 48 becomes effective. This is taken advantage of so as to open the auxiliary switch 40 upon movement of the shift lever 35 and prior to finger 48 becoming effective.

Secured to or formed integrally with the locking lever 45 is an arm 51 which extends across and then rearwardly alongside of the elements 41 of the auxiliary switch 40, and having secured to it an inwardly projecting wedge 52 of insulating material. The thin 55

free end of this wedge 52 is normally in close proximity to the contacts 42 at their point of contact and the contacts 42 may be slightly beveled to facilitate the entry of wedge 52 between them. When the shift lever 35 engages the cam 44 and moves it slightly, the locking lever 45 is moved and the wedge 52 is inserted between the contacts 42, forcing the lower one down, opening the switch and breaking the motor circuit. The arrangement of pivot 46, cam 44 and wedge 52 is such that only a slight movement of the cam 44 is necessary to break the circuit, and this may be accomplished before finger 48 becomes effective, so that the latter has only to receive the strain due to the momentum of the parts. The entire operation has been shown in its three steps in Figs. 4, 5 and 6. Fig. 4 shows the parts in normal position; Fig. 5 shows the same parts with lever 35 moved sufficiently to break the motor circuit but not to bring finger 48 into action; and Fig. 6 shows the lever 35 moved sufficiently to not only break the motor circuit but also to render finger 48 effective.

Reference has been made herein to application Ser. No. 226,418, particularly to indicate the use of this invention in connection with an automatic carriage shift during the depression of the plus or minus bar; to application Ser. No. 262,574, particularly to indicate the applicability of the invention to automatic multiplying and full-automatic division mechanism; and to the Britten application for a full showing of the shift or reversing lever mechanism for the counters, and, of other related mechanism.

In conclusion, it may be stated that the present invention discloses means for breaking the motor circuit when the carriage is moved out of operative position either automatically or manually, and when the shift or reversing lever is in any position other than its two proper operative positions.

What I claim is:

1. In a calculating machine, the combination of a carriage, means for raising and moving said carriage from one to another of a plurality of operative positions, operating devices for said machine including an electric switch, and means operable by said carriage for effecting closing of said switch when said carriage is in any one of a plurality of its operative positions and for effecting opening of said switch when said carriage is raised from operative position.

2. In a calculating machine, the combination of indicator dials, a driving motor, an electric switch operatively connected to said motor, a reversing lever operatively associated with said dials, a lever formed with a cam operatively associated with said reversing lever, and a switch-controlling element on the second said lever.

3. In a calculating machine, the combina-

tion of a driving motor, an electric switch operatively connected to said motor, a carriage including means for effecting closing of said switch, dials mounted in said carriage, a reversing lever operatively associated with said dials, and means operable by said reversing lever for effecting opening of said switch. 70

4. In a calculating machine the combination of a driving motor, a carriage movable to any of a plurality of operative positions, means controlled by said carriage and including an electric switch and whereby said motor may be rendered effective and ineffective, dials on said carriage, a reversing lever 75 for said dials, and means operable by said lever and associated with said switch for controlling said motor. 80

5. In a calculating machine, the combination of dials, a driving motor, a member 85 driven by said motor, an electric switch, a reversing lever, a locking lever including an element for opening said switch and an element for locking said member and an element co-operative with said reversing lever whereby said reversing lever may effect opening of said switch and thereafter effect locking of said member. 90

In testimony whereof I affix my signature. FRED MASCH. 95
